UNITED STATES PATENT OFFICE.

FRANCIS W. HETTINGER, OF READING, PENNSYLVANIA.

WINDOW FRAME AND SASH.

SPECIFICATION forming part of Letters Patent No. 251,778, dated January 3, 1882.

Application filed September 12, 1881. (No model.)

To all whom it may concern:

Be it known that I, FRANCIS W. HETTINGER, of the city of Reading, county of Berks, State of Pennsylvania, have invented a new and useful Improvement in Window Frames, Sashes, and Screens, and the Hanging of the Same, of which the following is a specification.

This invention relates to that class of window frames and sashes wherein the sashes are adapted to be removed from the same for the purpose of cleaning or repairs, and is an improvement on the various plans which have preceded it.

The quick removal and replacement of a window-sash, without disfiguring the case or frame or calling into service a carpenter or joiner, has long been a desideratum. My invention places such sash within the reach of all.

Referring to the drawings herewith, in which similar figures indicate similar parts, Figure 1, Sheet 1, is a front elevation of a window frame and sash according to my invention; Fig. 2, Sheet 1, the same with one of the sashes removed, showing the suspension-guides; Fig. 25 3, Sheet 1, a plan view of case, sash, and appliances, partly in section; Fig. 4, Sheet 2, an enlarged view of a sash, partly sectioned on the side, showing the spring, suspension-hooks, and needle-guide; Fig. 5, Sheet 2, an alternative summer sash or screen; Fig. 6, Sheet 2, a perspective view of the tubular suspension-guide and cord-fastener; Fig. 7, Sheet 2, extension of guide; Fig. 8, Sheet 2, a partial sectional elevation of the sash-frame, suspension-hooks, and guide, showing the same connected; Fig. 9, Sheet 2, elevation and plan of the spring, suspension-hooks, and needle-guide. Fig. 10, Sheet 3, represents the tubular guide in connection with the sash-hook and a section of the key inserted between the spring O and abutment P². Fig. 11, Sheet 3, represents the tubular guide in connection with the sash-hook and a section of the key partially turned so as to be just at the point of releasing the sash. Fig. 12, Sheet 3, represents the tubular guide released from the sash-hook connection with a section of the key returned to its normal position for withdrawal.

A A' represent the frame facings; B, the frame; B'; the inner face of the case. B² are semicircular grooves extending from the sill to the top of the inner face of the window-frame.

C is the upper and C' the lower glazed sashes. D is a screen-sash. E is an escutcheon facing a key-hole on each side of the sashes. F is a round hollow cast-iron suspension-guide and cord-fastener, having on its back a supplemental guide, G, provided with a hook, G', and having a bell-mouthed passage, G², next to the suspension-guide F, for the needle-guide. H is an abutment, with an open slot of a suitable width to admit the cord for the suspension of the sash. I is a sweep or whistle-mouth for the entering and withdrawing of the sash-cord knot. J is a supplemental guide-piece; K, a suspension spring hook-support, and extended at L to form the needle-guide; M, a spring hook-pad; N, a screw-hole for fastening to the sash; O, a spring-suspension, having hook-heads P P' and a screw or rivet, O', to secure it to the pad M. R are pulley-sheaves, having their case-faces concave to correspond with the grooves B² in the jambs of the frame. S are the sash-weights.

It will be noticed that the outer facing, A, of the frame B projects past the face of the grooved jamb-piece B', and forms a stop against which the outer or upper sash, C, rests and slides. The facing A' upon the interior does not project, but is made flush with the face of the jambs. The depth of the jambs B' is taken up by the thickness of the sash C C' without the intervention of a parting-stop, as is customary.

The jambs B' are grooved from end to end with two semicircular grooves of such diameter as will nicely fit the suspension-guides F and yet permit their free movement therein. Pul'ey sash-cord guides are placed at the usual distance from the top of the jambs, and they are provided with concave-faced cases, which are let into the jambs at the grooves B², flush with the same.

The sashes are grooved at C², with a semicircular groove corresponding with the grooves B² in the jambs, and, in addition thereto, for about two-thirds of the depth of the sash from the top of the same, with a square groove, C³, this being supplemented by an added mortise for the play of the suspension spring-hooks P P' therein. The vertical stiles of the sash having been prepared as described, the spring and needle-piece O K is inserted and secured to the sash at the proper point to connect the sash by the hook P with the hook G'

of the suspension-guide F when the guides are at the top of the frame. The escutcheons E are placed so that a flat key inserted with its edges vertical at the point P² and turned over 5 on its side will press the spring O away from the needle-block, and when the hooks P or P' are in contact with G', will release the same. The inner face of the frame-cap, immediately over the semicircular grooves B², is bored with 10 four holes of a corresponding diameter, and concentric therewith, of such depth that when the suspension-guide F is drawn therein the supplemental guide G shall be in a position to lock with the sash by contact of its hook 15 G' with the hook P of the sash attachment. The sash-weights are introduced into the weight-boxes, and the retaining-cords T are brought over the sash-cord guides in the usual manner, and a knot formed on the end at such 20 distance from the weight when resting on the sill in the weight-box as will insure the drawing of the guide F to the end of its movement in the hole in the cap of the frame previously described. The adjustments having all been made 25 relative to each other, as described, the cords T are drawn down and the knots, by the mouth I, introduced into the tubular guide F, the weight S drawing the same against the abutment H. On releasing the guide it ascends 30 the groove B² and passes into the cap-hole above until brought to a stop therein. The guides having been thus suspended, the sash C is inserted between the jambs and raised until the hooks P have passed over the hooks G' 35 and interlocked therewith, the needle-guide L having entered the slot G'. The sash is then drawn down to the sill, the finger placed on top of the guide F, projecting above the same, and held until the sash is raised sufficiently to 40 pass the second hook, P', over G' and interlock it therewith, when the top of the guide and sash-rail will be even. In this manner each cord is successively manipulated and the sashes are hung. To release the sash, the cord T is 45 held by the hand and its pressure relieved, a key being turned in the escutcheon-hole, as described, and the guide will be released and rise and be carried to the top of the frame, as before described. This having been done to both 50 sides of the sash, there is no obstruction to its removal.

It will be seen from the above description how easily changes can be made in the summer season from glazed sashes to screens, in 55 whole or part, it only being necessary to provide sashes for the screens of a similar character to those of the glazed sash having the same spring suspension-hooks O K attached thereto.

60 Any person with sufficient strength to handle the sash can enter them, make the attachment, change them from glazed to screen sash, or vice versa, as they may desire.

The guides F are to be of the full length of 65 the movable sash to which they are applied and have a section of the shell removed from

the whistle-mouth I to the top to pass the cord T freely in and out.

To save weight of metal and reduce the cost of the same, I cut the guide off a short distance below the whistle-mouth I. This portion being a full cylinder, I tap the interior with a coarse thread, and turn up hard wood of the same diameter as the guide, with a tenon at one end, of such diameter that on insertion 75 and turning in the guide F it shall have a corresponding thread formed upon it and interlock therewith, forming the piece J when detached therefrom, the combined length of F and J being equal to the length of the side of 80 the sash.

To carry out my invention fully, I prefer to have the face of the jambs B' unpainted, being finished in oil, which will give a smoothness of motion and allow a nicety of fit unattainable if painted. 85

Many lives are lost annually during house cleaning and limbs broken by falls from the upper stories of buildings in attempting to clean large windows upon the outside while in place. 90 With my improved sash in place there is no risk to incur; the ease with which they can be removed and the additional facility of cleaning gained thereby will remove all cause for accident. Finally, my combination of a round 95 guide and grooved seats in sash and frame forms a joint impervious to wind, dust, or rain.

Having described my invention, its operation, and advantages, I desire to claim by Letters Patent the following:

1. A window-frame, B, having its inner jambs, B', grooved longitudinally on the inner face, one groove for each independent sash to slide in the frame, the lintel bored with a concentric hole, as specified, over each groove, and sash-cord attachments adapted to play in said grooves, the outer facing-piece, A, projecting beyond the inner face of lintel and jambs, and the interior facing-piece, A', having its inner edge flush with the face of the lintel and jambs, substantially as shown, and for the purpose described. 105

2. The glazed sash C or screen-sash D, having its vertical stiles grooved at C² to correspond with B² in the frame and provided with 115 a square groove, C³, spring suspension-hooks, and needle-guides O K L, escutcheon-holes E, and sash-cord attachments adapted to play in said groove, substantially as shown, and for the purpose specified. 120

3. The independent movable tubular sash-guide and cord-fastener F, cut away on the jamb side for about two-thirds of its length to permit the entrance of the cord, having an abutment, H, with a reduced slot to catch the knot of the 125 cord T, a whistle-mouth, I, a supplemental guide, G, provided with a hooked head, G', and a bell-mouthed passage, G², through the same, the lower end of the tube being threaded, substantially as shown, and for the purpose set forth.

4. The double-hooked spring-suspenders O,

- having heads P P', secured to pad M of the needle-guide block K, and in combination therewith, substantially as shown, and for the purpose described.
5. The needle-block K and guide-needle L, provided with pad M and screw-hole N, in combination with the double-headed spring-suspenders O, connected by the rivet or screw O', substantially as shown, and for the purpose specified.
10. The combination of the frame B with semi-circular grooved jambs B', sash-cord guides R, facing-pieces A A', and guide-holes in lintel, as described, with the tubular suspension-guide F and extension J, and the sash-cord T, substantially as described, and for the purpose set forth.
15. The combination of a window-frame, constructed and arranged as described, with the glazed sash C or screen-sash D, the spring-suspenders and needle-guides O K L, and the suspension tubular guide F, the hook G', cord T, weight S, and guide-sheaves R, substantially as shown, and for the purpose specified.
20. The combination of the hard-wood guide J, having a threaded tenon, with the tubular suspension-guide F, substantially as shown, and for the purpose set forth.
25. The combination of the sash C or screen D with the grooved jambs B' and suspension-guides F, constructed as described, whereby they are adapted to be removed or replaced, substantially as specified, and for the purpose set forth.
30. The combination of the sash C or screen D with the grooved jambs B' and suspension-guides F, constructed as described, whereby they are adapted to be removed or replaced, substantially as specified, and for the purpose set forth.
